ABSTRACT

A new and distinct cultivar of Impatiens plant named Fiji, characterized by its large, pastel pink flowers, compact growth habit with excellent self-branching without pinching, medium green foliage, very early and uniform flowering, and its floriferous habit.

1 Drawing Sheet

1

The present invention relates to a new and distinct cultivar of plant known as Impatiens and commercially known as New Guinea Impatiens. The new cultivar is known by the cultivar name Fiji, and was developed by the inventor Ludwig Kientzler in Gensingen, Federal Republic of Germany by crossing the cultivar designated Delias (seed parent) with the cultivar designated E-170 (pollen parent). Delias is disclosed in a pending application of applicant.

Asexual reproduction by terminal (stem tip) cuttings, taken by me or under my supervision at Gensingen, Federal Republic of Germany, has shown that the unique features of this new Impatiens are stabilized and are reproduced true to type in successive propagations.

The following characteristics distinguish the new Impatiens from both its parent varieties and other cultivars of this general type known and used in the floriculture industry:

1. Very compact growth with good branching habits. 20 Plants in 16.5 cm pots were 14 cm tall and 28 cm wide, eight weeks after planting.

2. Large pastel pink flowers with a red eye. Open flowers measure up to 5.5 cm or larger.

3. Early flowering and very floriferous. Flowers almost completely cover the plant. Plants in 16.5 cm pots were in flower 6 weeks after planting. 25

4. Medium green foliage.

5. Well suited for 4" pot culture.

30 Fiji can be compared in certain respects to the cultivar Tahiti, disclosed in a pending application of applicant. The flower color of Fiji is similar to Tahiti, but not as dark. Also, the growth habit of Fiji is more compact than Tahiti.

The accompanying colored photograph is a top perspective view of the new cultivar, showing color as true as it is reasonably possible to obtain in a colored reproduction of this type.

The following is a detailed description of my new 40 Impatiens cultivar based on plants grown under commercial practice in Encinitas, Calif. Plants were started as rooted cuttings and were transplanted in mid-December into 16.5 cm (6.5 inch) pots, one pot per plant. By mid-February, plants were growing vigorously and 45 were in flower. The values, measurements and observations noted below were taken from plants in full bloom in mid-February.

2

Color references are made to the Royal Horticultural Society Colour Chart (R.H.S.), except where general terms of ordinary dictionary significance are used.

5 Parentage: Cross between Delias (seed) and E-170 (pollen).

Asexual reproduction:

A. *Cutting type*.—Tip, with stems 2-3 cm long developing to 4-5 cm after 21 days in propagation.

B. *Time to initiate roots*.—8-10 days at 23° C.; nicely developed root mass in 18-21 days.

C. *Rooting habit*.—Numerous, fibrous, adventitious roots from the stem.

15 Plant description:

A. *Form*.—Symmetrical, bush shaped, flowering herb, with self-branching characteristics giving the plant a full appearance. Pinching is not recommended since it does not enhance branching and only delays flowering by removing flower buds.

B. *Habit of growth*.—Vigorous, self-branching habit, producing whorls of leaves and flowers. Growth is indeterminate and flowering is continuous.

C. *Foliage description*.—Leaves are simple. Lower leaves on stems are opposite. Higher leaves in whorls of 3-5, but predominately 5. 1. Leaf shape: Broadly lanceolate to ovate. Leaf blade tips are acuminate; bases are attenuate to acute. 2. Leaf blade size: Mature leaves mostly 11 cm long by 4 cm wide. 3. Petiole length: 4-5 cm. 4. Leaf margin: Very finely ciliated and finely serrated. 5. Leaf texture: Slightly rugose. a. Upper surface: Glabrous. b. Under surface: Glabrous. 6. Leaf color: Medium green. a. Upper surface: Near, but darker than 147A. b. Under surface: Greyed green, between 191A and 191B. 7. Venation: Pinnate.

40 Flowering description:

A. *Flowering habits*.—Very floriferous. Flowering is continuous. Flowers develop progressively around the whorl of leaves, taking 5-7 days from buds which show color, to bloom. Flowers are single and large, lasting for 2-3 weeks.

B. *Natural flowering season*.—Flowering is indeterminate and occurs throughout the year. Quantity of flowers increases with increasing light inten-

sity and duration. However, floriferousness may wane during hot summer days in temperate climates.

C. *Flower buds*.—Ellipsoidal and covered with 3 sepals plus 2 rudimentary sepals fused into the 5 under surface of the superior petal. A spur originates from the base of the inferior sepal. Spur is red and approximately 5.5 cm long.

D. *Flowers borne*.—Singly, on reddish pedicels about 5 cm long.

E. *Quantity of flowers*.—Usually two flowers per leaf. Flowers occur progressively around the whorl of leaves so that tight buds to mature flowers are visible at the same time.

F. *Petals*.—Petals open nearly perpendicular to the 15 pedicel so the plane of the flower surface is nearly flat. 1. Number of petals: Five (5) petals, all overlapping. 2. Shape: All petals are heart-shaped. Superior petal has a broad base. Other petals have a pointed base. 3. Color: Pastel pin 20 with a small red eye. a. Upper surface: Near 62C.

55

60

(i) Base of petal: Near 61B. b. Under surface: Near 62C. 4. Flower size: Up to 5.5 cm or larger in diameter.

G. *Reproductive organs*.—Flowers are monoecious. 1. Stamens: Five (5), broad and fused to form a tube around the ovary; tinged with red. 2. Anther: Hooded and cream colored. 3. Pollen: Cream colored. 4. Stigma: Five pointed star, colorless. 5. Styles: Very short. 6. Ovary: 5-celled, 4-5 mm long until fertilized. Grows to 1 cm or longer after fertilization; green.

Resistance to disease: Good resistance to common stem and root disease, Rizoctonia and Pythium. Botrytis may be a problem in humid or mist propagation environments, but no greater than with other New Guinea Impatiens cultivars.

I claim:

1. A new and distinct cultivar of *Impatiens* plant named Fiji, as illustrated and described.
